CURRENT METER.

Original application filed October 17, 1925, Serial No. 63,089. Divided and this application filed July 13, 1926. Serial No. 122,244.

This invention relates to electrical make-and-break contact chambers, and more particularly to such chambers in which the motion producing the make and break is furnished by a moving shaft and in which the parts are so combined that the power required to drive the mechanism is reduced to a minimum. A contact chamber fulfilling these conditions is highly desirable for electrical 5 counting and indicating devices, for instance, in electrical current meters. In meters of this character, means driven by the fluid current, as air, water or the like, serve to drive a shaft mounted in a suitable support such, for 10 example, as a yoke, one arm of which carries the contact chamber into which the end of the shaft projects and effects a make-and-break contact with a brush forming part of an electric circuit, the make-and-break of the circuit 15 being effected either directly through the contact and break of contact of the brush with the shaft, or through make-and-break contact with a secondary shaft driven thereby.

In my application Serial No. 63,089, filed 25 October 17, 1925, of which this application is a division, I have described and claimed a construction of shaft peculiarly designed to be readily disassembled for cleaning or transportation and in which the bearings are protected from sediment and other foreign matter which would cause undue friction that would interfere with the accurate function 30 of the device.

In current meters, the driving connection 35 between the main shaft and the supplemental shaft in the contact chamber, which connection is usually in the form of a worm and gear, must be nicely adjusted so as to effect accurate driving of the transverse shaft without un- 40 due friction or binding action. The contact between the current-driven element and the so-called "brush" is of extreme importance, since the accuracy of the results obtained by use of the current-driven motor depends 45 upon the accurate functioning of this brush. Heretofore this brush has been in the form of a spring, one end of which is secured in the wall of the contact chamber, and the other end of which is bent into the form of a V, the 50 point of the V being placed in position to make contact with the projection or projections on the current-driven shaft. This brush

is necessarily very minute and, by reason of its construction, it must be accurately placed so that the point of the V thereon will make the proper contact. Moreover, this brush is necessarily insulated from the wall of the contact chamber in which it is carried, and it is extremely desirable to remove the brush and replace the same without disturbing the 55 insulation of the brush mounting in the walls of the contact chamber.

It is an object of the present invention to provide means for nicely adjusting the engagement between the worm on the main 60 shaft and the worm gear on the countershaft, to the end that the same may function with great accuracy. This is of importance not only in the assembling of the parts when new, but to compensate for wear between the parts 65 resulting from extended use.

A further object is to provide a contact brush so constructed that it may be readily inserted in position in the contact chamber so as to make required make-and-break contact; that shall be flexible to reduce friction of contact; that shall not be liable to be broken; and in which the contact brush and the carrier therefor are removable as a unit and 70 without disturbing the insulation element.

With these objects in view, the invention consists in so mounting the worm gear on the countershaft and the countershaft itself in the contact chamber that the gear may be nicely adjusted with relation to the worm on the 75 main shaft, preferably, this is accomplished by mounting the countershaft in bearings carried by a disk in the bottom of the contact chamber and placing the worm gear on said countershaft to one side of the radius of the 80 chamber which is perpendicular to said shaft. As the main shaft projects into the chamber at one side thereof, it will be apparent that, by shifting the disk bearing the countershaft around the center of the contact chamber, any 85 degree of adjustment required with relation to the worm carried by the main shaft may be secured.

Furthermore, the invention consists in providing a flexible contact brush composed of a strand of wires and preferably having a small knob secured on the end thereof to effect contact with the shaft, said strand of wires being mounted at the end opposite the knob in a car-

rier which is removable as a unit from the chamber without disturbing the insulation therefor.

The invention further consists in the details of construction and arrangement of parts as will be hereinafter more fully described. The invention involved is capable of receiving a variety of mechanical expressions, one of which, for the purpose of illustrating the invention, is shown in the accompanying drawings, but it is to be expressly understood that these drawings are for the purpose of illustration only and are not designed to define the limits of the invention, reference being had to the appended claims for this purpose.

In said drawings:

Fig. 1 is a side elevation of one form of current meter to which the invention is applicable, parts being shown in section;

Fig. 2 is a sectional view of the contact brush and its mounting, parts being shown in elevation;

Fig. 3 is an extended or exploded view of the contact brush and its mounting, with the parts shown in perspective;

Fig. 4 is a top plan view of the contact chamber and its contained parts, with the cap removed to expose said parts in the interior of the chamber;

Fig. 5 is a perspective view of the counter-shaft in its adjustable mounting.

Referring to the drawings, in which like reference numerals indicate like parts throughout the several views, there is shown, for the purpose of illustration, a cup-driven current motor mounted in a suitable yoke, but it is to be expressly understood that the invention may be applied to other forms of motor without departing from the spirit thereof. In the drawings, 1 indicates a shaft having at one end a tail-piece 2 removably secured thereto and at the other end a yoke composed of arms 3, 3'. Passing through the shaft 1 is a suitable staff 4 on the lower end of which is usually secured a weight (not shown) of suitable form and character to maintain the device in upright position, all as will be readily understood by those familiar with the art. A cup wheel 6 is mounted on a shaft 7, whose bearings are supported by the arms 3, 3' of the yoke. All of these parts may be of the usual or any suitable preferred construction, though in the present instance the shaft 7 is shown as of the form described and claimed in by aforesaid application.

Referring to Figs. 1 and 2, 8 is a contact chamber which is shown as substantially cylindrical in cross-section and provided with a cap 8' screw-threaded or otherwise secured in the top of the chamber. This contact chamber is provided with a downwardly projecting hollow arm 9 by means of which said chamber is mounted in an opening 10 formed in the upper arm 3 of the yoke, the same being

held in position by set-screw 11, preferably entering an annular groove in the downwardly projecting arm 9. In this downwardly projecting part 9 the shaft 7 takes its upper bearing.

Referring now to Figs. 1, 2 and 3, 26 is a strand of very thin flexible, elastic wire having a metallic bead 27 secured to one end thereof; the other end is secured to a stem 28 having a collar 29. This stem fits smoothly in a sleeve 30, with the collar 29 abutting against the outer end thereof, and a nut 31 having an interiorly projecting flange is screw-threaded onto the outer end of the sleeve 30 until it engages the collar 29 on the stem 28, thereby firmly holding said stem and with it the contact brush 26 in position in said sleeve. The sleeve 30 is preferably provided with a flange 32, and the interior end of the sleeve is screw-threaded into an insulation block 33, which block is also provided with exterior screw-threads, as clearly shown in Figs. 2 and 3. Referring, now, to Fig. 1, the insulation block 33 is screw-threaded into a thickened wall 34 of the chamber 8, with the beaded end 27 of the brush in a position to contact with a ridge 25 on the rod 12 at each revolution thereof, and the wire 35 leading to a battery 35' (which is connected by a wire 35'' with the staff 4) is clamped against the nut 31 by a binding nut 36.

It will be observed that in placing this brush in position it is only necessary to give the wire strand a slight sidewise bend to insure that it will properly contact with the rib 25, and this is effected without any circumferential adjustment of the brush, such as would be necessary when a spring having a V-shaped end is employed. Moreover, the brush being composed of a strand of wires is not readily broken, thus overcoming a difficulty frequently experienced when a single piece of spring-wire is employed. These parts are extremely delicate, the same being shown here on an enlarged scale, and by the construction here shown they can, notwithstanding their minute construction, be readily and accurately placed in operative position without danger of breakage of the parts.

To remove the brush, it is only necessary to disconnect the wire 35 and unscrew the nut 31, when the brush, together with the stem 28, can be removed intact, as shown in the upper part of Fig. 3, and that without disturbing the insulation 33 or the sleeve 30. All the operations can be performed either with the fingers or the use of a very small wrench. To restore the parts to position, it is only necessary to insert the brush, together with the stem 28, in the sleeve 30 and tighten the nut 31.

Referring, now, to Figs. 1, 4 and 5, 37 is a crescent-shaped disk, whose exterior circumference corresponds, except for a cut-

away portion, to the interior circumference of the contact chamber. Projecting upward from said disk are two bearing posts 38, 38, in which the shaft 39 is mounted to turn. 5 The bearing posts 38, 38 are so positioned that the shaft 39 extends across the contact chamber 8. Keyed to the shaft 39 and to one side of a radius of the chamber perpendicular to the shaft, is a worm wheel 40, and the shaft 10 is also provided with a plurality of radial projections 41 with which the brush 26 makes contact at each revolution of the shaft. The disk 37 has a curved slot 42 formed therethrough and through this slot a screw 43 (Fig. 4) extends and is screw-threaded into the bottom of the contact chamber 8, as clearly shown in Fig. 1. By loosening the contact screw 43, the disk 37 may be moved a small distance around its center so as to bring the worm wheel 40 into accurate working engagement with the worm 24 (Fig. 1) on the projecting end of the rod 12 forming part of the shaft 7, when the screw 43 and the parts are thus held in correct operative relation. By this means, provision is not only made for the correct initial adjustment of the parts for proper engagement between the worm and worm wheel, but also for such adjustment as may be necessary to take up 25 any wear between these parts.

It will be observed that all of the parts of the brush are so constructed that the brush may be readily removed without disturbing the insulation between said brush and the 30 contact chamber and as readily inserted in proper position without the use of tools; that the proper contact between the worm wheel 40 on the shaft 39 and the worm 24 on the shaft 7 may be adjusted with a nicety, and all without the exercise of more than the ordinary skill.

It will be readily appreciated by those skilled in the art that the inventive idea illustrated in the drawings may be embodied in 45 other forms than that herein shown without in any way departing from the spirit of the invention, and all such forms are intended to be included in the appended claims.

What is claimed is:—

1. In an electrical make-and-break device, the combination of a contact chamber, a driven shaft projecting into said chamber to one side of the center thereof, a worm on said shaft, a countershaft mounted transversely of said chamber and having a contact point thereon, means for bodily adjusting said countershaft around the center of said chamber, a worm gear on said countershaft to one side of a radius of said chamber that is perpendicular to the countershaft, said gear operatively engaging said worm, and a contact brush mounted in said chamber in position to engage said contact point at each revolution of said countershaft.
2. In an electrical make-and-break device, 65 the combination of a contact chamber, a driven worm shaft projecting into said chamber to one side of the center thereof, a countershaft extending transversely of said chamber and having a contact point thereon, a disk 70 supporting said countershaft, said disk being adjustable around the longitudinal center of said chamber, a worm gear on said countershaft to one side of the radius of said chamber that is perpendicular to the countershaft, 75 said gear operatively engaging the worm shaft, and a contact brush mounted in said chamber in position to engage said contact point at each revolution of said countershaft.
3. In an electrical make-and-break device, 80 the combination of a cylindrical contact chamber, a driven worm shaft projecting into said chamber to one side of the axis thereof, a disk mounted to be turned in said chamber 85 around the axis thereof, a countershaft mounted on said disk and extending transversely of said chamber and having a plurality of contact points thereon, a worm gear on said countershaft to one side of the radius 90 of said chamber that is perpendicular to the countershaft and operatively engaging the worm shaft, a flexible contact brush, a mounting therefor extending through the walls of said chamber and insulated therefrom, said 95 brush being in position to engage said contact points at each revolution of said countershaft.
4. In an electrical make-and-break device, 100 the combination of a contact chamber and a contact brush, said brush comprising a flexible strand of metallic wires, a stem to which one end of said strand is connected, an insulated mounting for said stem extending through the walls of said chamber and having 105 a longitudinal opening through which said stem extends, and means separate from said stem and mounting removably securing said stem slidably in said mounting, whereby said stem and brush may be removed from the 110 chamber without disturbance of said mounting or the insulation therefor.
5. In an electrical make-and-break device, 115 the combination of a contact chamber, a threaded sleeve of insulating material in the wall of said chamber, a second threaded sleeve secured in said insulation sleeve, a rod having an exterior shoulder passing through said second sleeve, means engaging said shoulder and locking said stem to said last-mentioned 120 sleeve, and a contact brush secured to the inner end of said stem, whereby said brush and stem may be removed from the chamber without disturbance of the mounting therefor.

In testimony whereof I have signed this specification.

CARL H. AU.
